UNITED STATES PATENT OFFICE

ERNEST AUGUST WEKERLE, OF LOS ANGELES, CALIFORNIA, ASSIGNOR TO DAVID BLANKHORN, OF LOS ANGELES, CALIFORNIA

SELF-SEALING CLOSURE VALVE FOR COLLAPSIBLE TUBES

Application filed March 10, 1932. Serial No. 598,061.

This invention relates to collapsible tubes and more particularly to a self-sealing closure for a collapsible tube.

An object of this invention is to provide 5 a self-sealing means for a collapsible tube which can be mounted on any conventional tube, said means operating automatically to close the discharge port of the tube upon release of pressure within the tube.

10 Another object of this invention is to provide an exceedingly simple automatically closing means for a collapsible tube which embodies only two parts so that the device will not readily get out of order during the 15 use of the tube and will effectively seal the discharge nozzle or port so as to prevent drying out of the material within the tube.

The above and various other objects and 20 advantages of this invention will in part be described in and in part be understood from the following detailed description of the present preferred embodiment, the same being illustrated in the accompanying drawing, wherein:

25 Figure 1 is an enlarged fragmentary side elevation of a collapsible tube partly broken away and in section having a device constructed according to the preferred embodiment of this invention mounted therein, the 30 device being shown in longitudinal section and in closed position.

Figure 2 is a view similar to Figure 1 but showing the device in open position.

Figure 3 is a sectional view of the fixed 35 valve member.

Figure 4 is a bottom plan view of the fixed valve member.

Figure 5 is a sectional view taken substantially through the longitudinal center of the 40 movable valve.

Figure 6 is a bottom plan view of the movable valve.

Referring to the drawing wherein like 45 characters of reference designate corresponding parts throughout the several views, the letter C designates generally a collapsible tube which is provided with a neck or nozzle 10. In order to provide means whereby the discharge neck or nozzle 50 10 may be automatically closed upon release

of pressure on the material within the tube C, I have provided a fixed member including a cylindrical portion 11 which is mounted within the interior of the neck 10 in a fixed position relative to the neck.

An axially disposed stem 12 is mounted 55 within the cylindrical body 11 and has a connecting plate 13 connecting the inner end of this stem 12 to the inner end of the cylindrical body 11. The inner plate or bottom 60 13 is provided with a plurality of discharge openings 14 which are disposed about the periphery of the post or stem 12, and this inner bottom or plate 13 is also provided with opposed slots 15, the purpose for which 65 will be hereinafter described. The outer end of the stem 12 is closed and is curved in the form of a hemisphere, as at 16, and this curved portion constitutes a valve seat which is, in the present instance, disposed 70 outwardly from the outer edge of the cylindrical body 11.

A movable valve member, generally designated as 17, which is provided with a cylindrical wall 18, is slidably mounted within 75 the interior of the fixed body 11, and this cylindrical portion 18 is provided at the inner edge thereof with a plurality of inwardly extending springs 19 which slidably engage in the slots 15 of the bottom or inner plate 13. The valve member 17 is provided at the outer end thereof with a cap 20 having a discharge port 21 therethrough, which port 21 is adapted to engage over the head 16 of the stem 12 under the action of 80 the springs 19 so as to prevent the passage of any plastic material through the discharge port 21.

In the operation of this device, the fixed 85 valve member 11 may be mounted within the neck 10 of the tube C, this mounting being either in the form of a press fit or a screw thread connection so as to prevent movement of the fixed valve member 11 relative to the neck 10 under the action of the pressure of the plastic material within the tube C. As 90 the tube C is collapsed and the material forced through the discharge ports 14 and into the interior of the cylindrical valve portion 11, the material will press against 95 100

the cap or plate 20 and force this movable valve member 17 outwardly against the tension of the springs 19, thereby permitting the material to pass outwardly through the 5 discharge port 21. When the pressure in the tube C has been relieved, the tension of the springs 19 will pull the valve member 17 inwardly of the cylindrical body 11 and the plate 20 will seat on the head 16 thereby preventing the passage of any additional material out of the tube.

It will be noted from the foregoing that an exceedingly simple collapsible tube closure has been provided wherein the operation 15 of the closure is automatic so that none of the material within the tube will exude from the tube unless pressure is applied to the tube so as to force the automatic valve member into open position.

20 While I have shown the spring members 19 as being formed with the cylindrical portion 18 of the valve 17, I do not wish to be limited to this particular construction, as these springs 19 may be either formed with 25 the member 18 or secured thereto in any desired or conventional manner.

It is, of course, understood that various changes and modifications may be made in the details of construction and design of the 30 above specifically described embodiment of this invention without departing from the spirit thereof, such changes and modifications being restricted only by the scope of the following claims.

35 What is claimed is:—

1. An automatic tube closure comprising a fixed valve member including a cylindrical member fixedly mounted in the discharge neck of a collapsible tube, an apertured plate 40 formed with the cylindrical member and positioned on the inner end thereof, an axial valve head carried by the plate, and a movable valve member engaging the valve head, said movable valve member including resilient means engaging the plate to constantly urge the movable valve member into closed position.

2. An automatic tube closure comprising a fixed valve member and a movable valve 50 member, said fixed valve member including a cylindrical body adapted to be fixedly positioned in the discharge neck of a collapsible tube, an inner plate formed with the body and having discharge apertures 55 therethrough, a valve head carried by the plate and disposed axially of the body, said movable valve including an outer plate having a discharge port axially thereof, the marginal edges of said port engaging the 60 head to close the port, and resilient fingers carried by the movable valve member and engaging the inner plate to constantly urge said outer plate into closed position.

3. An automatic tube closure comprising 65 a cylindrical member adapted to be fixedly

positioned on the discharge neck of a collapsible tube, an inner apertured plate formed with the cylindrical member, a valve head carried by the inner plate and disposed axially of the cylindrical member, a cup-shaped movable valve member telescoping within the cylindrical member, said movable valve member having a discharge port relatively smaller than said valve head and disposed axially thereof, and resilient fingers carried by the inner edge of said movable valve and engaging said inner plate to constantly urge the movable valve member into closed position.

4. An automatic tube closure comprising a cylindrical body adapted to be fixedly secured to the discharge neck of a collapsible tube, a plate formed with the inner end of the body, said plate having a plurality of discharge ports therethrough, a valve head formed with the plate and extending axially and outwardly thereof, a cup-shaped movable valve member slidably mounted within said body and having a discharge port axially thereof relatively smaller than said valve head, a plurality of inwardly directed resilient members carried by said movable valve, said inner plate having a plurality of slots to loosely receive said resilient members, said resilient members constantly urging said movable valve into contact with said head to close the discharge port.

In testimony whereof I hereunto affix my signature.

ERNEST AUGUST WEKERLE.
